UNITED STATES PATENT OFFICE.

EDGAR P. WOLF, OF RACINE, WISCONSIN, ASSIGNOR TO PERFEX RADIATOR COMPANY, OF RACINE, WISCONSIN, A CORPORATION OF WISCONSIN.

RADIATOR OF THE AUTOMOBILE TYPE.

1,410,356.

Specification of Letters Patent. Patented Mar. 21, 1922.

Application filed November 5, 1917. Serial No. 200,248.

To all whom it may concern:

Be it known that I, EDGAR P. WOLF, a citizen of the United States, and resident of Racine, in the county of Racine and State 5 of Wisconsin, have invented a certain new and useful Improvement in Radiators of the Automobile Type, of which the following is a full, clear, concise, and exact description, reference being had to the accompanying drawings, forming a part of this specification.

My invention relates to radiators of the automobile type and particularly relates to means for increasing the rate of heat transfer 15 between the water in the radiator and the air passing through the same.

For automobile radiators, the most efficient type of construction are those which have transverse openings from front to rear,—these openings being surrounded more or less by water as in the cellular type, or in the zigzag vertical tube type. I have found in practice that the air in the transverse openings or tubes often passes through, 25 becoming heated only on the outside. I have made experiments to determine whether this loss is of consequence.

I have found that the efficiency of the radiator can be considerably improved by 30 employing means for breaking up the straight flow of air as by suitable baffle members.

My invention aims to provide an improved radiator structure of increased efficiency 35 characterized by the use of baffles in the transverse air passages, for breaking up the direct air flow from front to rear so as to secure greater heat transfer between the side walls of the passages and the air passing 40 through them.

In a particular construction in which I have embodied the invention, I employ vertical water tubes with lateral corrugations forming air passages. In these air passages 45 I place baffles for giving the air a swirling motion, both to break up the direct current and also to increase the length of the path of travel. These baffles may be constructed of twisted strips, slitted from a single sheet 50 of metal or in the preferred form, they consist of wings or fins shaped like propeller blades, which are struck up from a sheet of metal.

In order to acquaint those skilled in the 55 art with one manner of constructing and

using my invention, I shall now describe in detail a particular embodiment of the invention in connection with the accompanying drawings, which form a part of the present specification.

60

Figure 1 is a cross sectional view taken on the line 1—1 of Figure 2;

65

Figure 2 is a side elevation of one of the radiator tubes with the baffle plate and baffle members in place;

65

Figure 3 is a similar view of a modification;

Figure 4 is a fragmentary detailed view of a modified form of baffle plate with baffle members or fins struck up from the side 70 edges of the metal;

Figure 5 is a sectional view taken on the line 5—5 of Figure 4 and showing the baffle plates in place, between two adjacent tubes;

75

Figure 6 is a fragmentary elevational 75 view of a modification, similar to that shown in Figure 4; and

Figure 7 is the section taken on the line 7—7 of Figure 6 and showing the baffle plates in place, between two adjacent tubes.

80

In Figure 1, the front ends of the water tubes 1 and 2 are shown in section. These tubes are complementary to each other, being formed with rounded depressions 3 and flattened projections 4 on the sides which 85 face the complementary tube. Each tube is made up of an outer plate 5 and an inner plate 6, suitably fastened together at their edges to form a closed tube and covered at the front and rear by open lattice work 90 plates 7 which cover the entire front and rear face of the radiator. The tubes are assembled with the rounded portions 3 registering with each other to form the round holes or air passages 8, and between adjacent groups of tubes the diamond-shaped openings 9 result. The outer portions of the rounded depressions 3 are slightly flared as shown at 10, to secure greater intake 95 openings, and to improve the appearance of the radiator.

The water channels in the tubes formed between the side walls 5 and 6 are zigzag in shape and thereby provide great superficial cooling area and a high ratio of cooling surface to water contents. These water passages are connected at their upper end to a common header or water chamber and likewise they are connected at their lower ends to a suitable header or water chamber.

105

110

A suitable casing, as is well understood by those skilled in the art, is also applied to complete the radiator.

As the construction of the headers and the casing is no part of the present invention, and as these features are well understood by those skilled in the art, no detailed description of the same is necessary.

In order to break up the flow of air through the air channels, or passageways 8, I provide baffle members of such shape as to throw the air outward from the center by centrifugal action,—these baffle members having fins of suitable form to effect this action.

As shown in Figure 2, I provide a baffle plate 12 which has the fingers, or fins 13, slotted therefrom at such points that these fingers or fins may lie within the openings 8. The plate 12 is continuous along the contiguous sides of the water tubes, being secured at the flattened projecting portions 4. The fingers or fins 13 are twisted into spiral form as shown in Figure 2 in order to give the air a swirling motion to break up the current thereof and to increase the length of the path of travel. It is apparent that the fingers or fins 13 may extend through the entire length of the passageways 8, or may extend only part way as shown in Figure 2.

In Figure 3, I have illustrated a front baffle plate 12 with fingers 13 projecting substantially half way of the length of the passageways 8 with a complementary plate 12' secured at the rear and having its fingers or fins 13' extending forward.

In Figures 4 to 7 inclusive, I have illustrated the baffle plates as comprising a single sheet of metal having fins struck up from the plates, these fins lying within the passageways 8.

In Figure 4 the plate 15 has fins 16 struck up alternately from the metal, along the edges 17 and 18, of the strips or portions 19 which lie between the flattened projections 4 of adjacent tubes. These fins 16 are given a twist or are warped to approximate in shape and effect helicoidal or screw propeller surfaces. The advantages of this construction are ease in manufacture, as the fins 16 may be struck up on a punch press or be otherwise formed by a very simple operation.

In Figures 6 and 7, I have illustrated a further modification in which small wings or fins 21 are struck up from the metal at such points that they will lie within the air passageways 8. These fins are preferably symmetrical and shaped so as to direct the air in a spiral whirl within the air passageways 8. The sheet or plate 20 from which they are struck up remains continuous along the strip 22, lying between the flattened projections 4, between adjacent tubes. The

fins 16, shown in Figures 4 and 5, may extend back throughout as much of the passageway 8 as is desired. In a similar manner, the fins 21 may be formed along as much of the passageway or tube 8 as is desirable. 70

In the form shown in Figures 6 and 7, it is also apparent that the fins 21 may be struck up by a very simple operation.

It is apparent that by this construction I have illustrated, a solid and substantial 75 radiator core is formed. The operation of assembling is simple and easy. The water tubes are easily connected together at their ends and connected to the corresponding headers. The baffle plates occupy very 80 little room, being formed of a light gauge of metal and in addition to their proper function of directing the air currents, they also serve as means for conducting the heat from the tubes to the air which strikes 85 them.

I do not intend to be limited to the precise details of construction shown or described.

I claim:

1. In a radiator, the combination of a pair 90 of water tubes having corrugations along their sides facing each other, said corrugations comprising rounded bottom portions and flat projecting portions, said round bottom portions registering to form a plurality 95 of circular air passages horizontally extending from front to rear, each of said circular air passages having a single, individual baffle member therein, each of said baffle members comprising a strip of metal twisted 100 in helical form to co-operate with the enclosing circular walls of its respective air passage for rotating the air passing therethrough.

2. In a radiator, the combination of a 105 pair of water tubes having corrugations along their sides facing each other, said corrugations comprising rounded bottom portions and flat projecting portions, said rounded bottom portions registering to form 110 a plurality of circular air passages extending horizontally from front to rear of said radiator, baffle means comprising a single sheet of metal having a continuous vertical edge and being provided with a plurality of 115 spaced slots therein terminating adjacent said edge, said spaced slots forming a series of projecting tongues spaced one from the other, the continuous vertical edge of said metal sheet being secured between the flat 120 projecting portions of water tubes, said tongues being spaced whereby a single, individual tongue extends into each of said horizontal air passages to co-operate with the surrounding circular walls of their respective air passages for rotating the air passing therethrough.

3. In a radiator, the combination of a pair 125 of vertical water tubes having lateral corrugations forming horizontally extending 130

air passages, and baffle means in each of said passages comprising fins projecting transversely across said air passages, said fins being shaped to rotate the air outwardly 5 into contact with the surrounding walls of said passages.

4. In a radiator, the combination of a pair of vertical water tubes having corrugations along their sides facing each other, said corrugations comprising rounded bottom portions and flat projecting portions, said rounded bottom portions registering to form a plurality of circular air passages extending horizontally from front to rear of said 10 radiator, a baffle plate interposed between said water tubes and secured between said flat projecting portions, said baffle plate being formed to provide a co-extensive series 15 of short fins in each of said circular air passages, said fins projecting transversely across said passages and being twisted to spirally rotate the air outwardly into contact with the walls of said passages.

5. In a radiator, the combination with adjacent metallic strips forming complementary parts of a series of air cells, of a metallic sheet arranged between said strips having struck out portions forming spiral deflectors in said air cells.

6. In a radiator, the combination with ad-

jacent metallic strips forming complementary walls of a series of air cells and having portions intermediate said cells parallel to each other, of a metallic sheet arranged between said strips and in contact with the 35 parallel portions thereof with intermediate portions extending diametrically across said cells, the latter portions having struck out wings forming spiral deflectors within the cells and openings through the sheet in the 40 direction of the spiral.

7. In a radiator, the combination with a plurality of water tubes fashioned to form complementary portions of a series of air cells, of a metallic sheet arranged between 45 said tubes extending across said cells, and wings struck out from said sheets fashioned to form spiral vanes in said cells.

8. In a radiator, the combination with complementary sections of an air cell, of a sheet clamped between said sections extending across said cell, having a portion struck out therefrom to form an obliquely arranged 50 deflector and an aperture for the passage of air to the opposite side of said sheet. 55

In witness whereof I hereunto subscribe my name this 1st day of November, A. D. 1917.

EDGAR P. WOLF.
